FEEDING MECHANISM

Claude L. Post, Chicago, Ill.

Application November 7, 1935, Serial No. 48,717

12 Claims. (Cl. 271—2)

This invention relates to feeding mechanism, and particularly to a device for feeding envelopes to a machine for operating upon the envelopes as, for example, a printing machine or the like.

5 Heretofore, considerable difficulty has been experienced in feeding envelopes to a printing machine, for example, when the flaps of the envelopes have become warped or curled, particularly adjacent their ends, due to the action of the adhesive applied to the flaps, or due to the action of atmospheric conditions on the adhesive. When the flaps are in such condition, the curl must be removed or smoothed out, and, unless extreme care is exercised, the curled portions of the flap 10 may be folded still further under or against the body of the flap, thus producing an undesirable condition of the envelope for passage through a printing machine or the like.

One of the objects, therefore, of the present invention is to provide a feeding mechanism having suitable means associated therewith for removing from the flaps any curl which may have developed therein.

Another object of the invention is to provide 25 novel means for directing the end portions of the flaps onto the feed table of the machine and into the guides by which the envelopes are guided to a printing roller, for example, in proper relation thereto.

30 A further object of the invention is to provide suitable driving means for the curl removing elements in order that they may be actuated in proper relation to other portions of the envelope feeding mechanism.

35 A still further object of the invention is to improve devices of the character described in sundry details hereinafter referred to and particularly pointed out in the appended claims.

One embodiment of the present invention is 40 shown for illustrative purposes in the accompanying drawings, in which:

Fig. 1 is a plan view of an envelope feeding mechanism shown in relation to a portion of the feeding mechanism of a printing machine and 45 illustrating my improved curl removing devices applied thereto;

Fig. 2 is a longitudinal sectional elevational view of the structure illustrated in Fig. 1, and taken substantially as indicated by the line 2—2 50 thereof;

Fig. 3 is a transverse sectional elevational view taken on the line 3—3 of Fig. 1 and illustrating the arrangement and structure of the curl removing device shown in Figs. 1 and 2;

55 Fig. 4 is a side elevational view of the driving

mechanism for actuating the curl removing devices; and

Fig. 5 is a perspective view of my improved feeding and curl removing mechanism shown in relation to the flap of an envelope, and illustrating 5 the manner of removing the curl therefrom.

In Figs. 1, 2 and 4 of the drawings, the present invention is shown in relation to a fragment of the feeding mechanism of a printing press of the character shown and fully described in Patent No. 1,758,536, issued to me May 13, 1930 and having a feed table indicated, as a whole, by the numeral 8, associated therewith, the feed table 8 being provided on its receiving edge adjacent its central portion with a plurality of fingers 9 inclined inwardly and away from the body of the table, or toward a magazine 11 adapted to contain a plurality of superposed envelopes E to be fed to the table 8 and thence to a printing machine or the like. 10

Positioned below the magazine 11 is a feeding mechanism indicated, as a whole, by the numeral 12, the specific details and operation of which are 15 fully described in Patent No. 1,730,477 issued to me October 8, 1929.

Briefly, the mechanism 12 includes a rotatable finger 13 adapted to engage the flap F of the lowermost envelope E positioned in the magazine 11 in a manner to unfold the flap thereof and move it outwardly into substantial alignment with 20 the body of the envelope between upper feed rollers 14 mounted on a shaft 15 and lower feed segments 16 and 17 mounted on a shaft 18, by which the flap F is engaged in a manner to feed the envelope from the magazine 11 onto the feed 25 table 8, the said rollers 14, segments 16 and 17 and the finger 13 being operated in a proper synchronism by means of gearing 19 (Figs. 1 and 2) and a drive chain 21 shown in Fig. 2, and as 30 clearly described in said Patent No. 1,730,477. 35

As previously stated, the flaps of envelopes frequently become warped or curled adjacent their end portions due to the action of the adhesive applied to the flap, or due to the action of atmospheric conditions on the adhesive in which case, 45 considerable difficulty has been experienced in feeding envelopes to a printing machine or the like, and to overcome this condition, the present invention contemplates a plurality of laterally spaced elongated longitudinally movable curl removing slide members 22 positioned beneath and at opposite sides of the magazine 11, the said slide members being mounted in ways 23 secured to the bottom of the magazine 11, and in substantial 50 alignment with the end portions of the envelope 55

flap F in a manner to engage said end portions to remove the curl or warp therefrom, preferably, when the flap F is in substantial alignment with the body of the envelope as illustrated in Fig. 5, 5 and to assist in directing the flap onto the said feed table 8.

For actuating the slide members 22 in proper relation to the feed segments 16 and 17 on the shaft 18, a pair of arms 24 are secured adjacent one of their ends to a rock shaft 25 and at their opposite ends by means of links 26 to brackets 27 secured to the underside of the respective slide members 22. For oscillating the rock shaft 25 in a manner to actuate the slides 22, an arm 28 is secured to the shaft 25 outside one of the frame members 29 and a tension spring 31 is connected at one of its ends to the arm 28 by means of a pin 32, and at its opposite end to a pin 33 mounted on the frame member in a manner to urge the arm 28 in one direction and to move the slide members 22 toward the envelope flap for removing the curl therefrom, the said movement of the slide members 22 being in advance of the segments 16 and 17 for assisting in 25 positioning the flap F in substantial alignment with the body of the envelope and in a position to be engaged by the feed rollers 14 and feed segments 16 and 17 as the latter are rotated to engage the envelope and advance it onto the 30 feed table 8.

For retracting the slide members 22, the shaft 18 is provided on its outer end with a disc 34 having a roller 35 mounted thereon and radially spaced from the line of rotation of the shaft 18, 35 and adapted to engage the arm 28 for moving the latter and rocking the shaft 25 against the action of the spring 31, thereby moving the slide members 22 in the opposite direction and into a position to engage the flap of the next succeeding envelope to remove the curl therefrom and assist in directing the flap onto the feed table 8.

By reference to Fig. 2, it will be noted that the finger 13 has moved the flap F to a vertical position where the outer ends thereof may be 45 engaged by the slide members 22 as illustrated in Fig. 5 in a manner to remove any curl therefrom before the flap is engaged by the feed segments 16 and 17 for advancing the flap and envelope to the feed table. Upon reaching the 50 feed table, the envelope is engaged by a pair of supplemental feed rollers 36 and 37 by which it is moved forwardly and longitudinally of the table 8 until the rear or following edge of the envelope is advanced sufficiently far to be engaged by lugs 38 on feed chains 39 by which the 55 envelope is further advanced to the mechanism as, for example, a type roller and platen of a printing machine or the like.

It will be observed from the foregoing description that the present invention provides a 60 novel construction and arrangement wherein the slide members 22 are moved in relation to the envelope in a manner to remove the curl from the end portions of the flap F in an efficient manner, and in advance of the engagement of 65 the flap by the feed segments 16 and 17, and wherein the slide members assist in directing the flap F onto the feed table in an uncurled or flattened condition, the inclination of the 70 fingers 9 adjacent the central forward edge portion of the feed table 8 insuring the lifting of the flap adjacent its central portion onto the central portion of the table.

Obviously, the present invention is not limited 75 to the precise construction and arrangement

shown and described, as the same may be variously modified. Moreover, all the features of the invention need not be used conjointly, as the same may be used to advantage in variously different combinations and sub-combinations.

What I claim as new and desire to secure by Letters Patent is:

1. In a device for feeding envelopes, the combination of a plurality of cooperating feeding means engageable with the flap of an envelope, a finger for engaging said flap for unfolding and moving the flap into a position adjacent said feeding means to be engaged thereby, and means engageable with said flap and relatively movable with respect thereto for removing any curl 15 from the outer end portions thereof.

2. In a device for feeding envelopes, the combination of a plurality of cooperating feed rollers and feed segments, means for engaging the flap of an envelope to unfold and move said flap into a position between said rollers and segments to be engaged thereby, and means engageable with the outer end portions of said flap and relatively movable with respect thereto for removing any curl 20 therefrom.

3. In a device for feeding envelopes, the combination of a plurality of rotatable feed rollers, rotatable feed segments cooperable with said rollers, means for engaging the flap of an envelope to unfold and move said flap into substantial alignment with the body of the envelope and into a position between said rollers and segments to be engaged and fed thereby, and means engageable with the inner face of said flap and relatively movable with respect thereto for removing any curl 30 therefrom.

4. In a device for feeding envelopes, the combination of a magazine for containing a plurality of superposed envelopes, a plurality of rotatable cooperating feed rollers and feed segments adjacent said magazine, means for engaging the flap of an envelope in said magazine to unfold and move said flap into a position between said rollers and segments to be engaged and fed thereby, and means slidably mounted on said magazine adapted to engage the outer end portions of said flap with respect thereto for removing any curl 40 therefrom.

5. In a device for feeding envelopes, the combination of a magazine for containing a plurality of superposed envelopes, a plurality of rotatable cooperating feed rollers and feed segments adjacent the lower end of said magazine and at one side thereof, means for engaging the flap of the lowermost envelope in said magazine to unfold and move said flap into substantial alignment with the body of the envelope and into a position between said rollers and segments to be engaged thereby and drawn from said magazine, and slide members mounted beneath said magazine and relatively movable with respect to said lowermost envelope and engageable with the end portions of the flap thereof for removing the curl therefrom.

6. In a device for feeding envelopes, the combination of a magazine for containing a plurality of superposed envelopes, a plurality of cooperating feed members adjacent the lower end of said magazine and at one side thereof, driving means for actuating said feed members, means for engaging the flap of the lowermost envelope in said magazine for unfolding and moving said flap into substantial alignment with the body of said envelope and into a position between said feed members to be engaged 75

thereby and drawn from said magazine, a pair of elongated laterally spaced longitudinally movable slide members positioned respectively in substantial alignment with the respective outer 5 end portions of said flap and engageable therewith for removing any curl therefrom, and means operatively related to said driving means for actuating said slide members.

7. In a device for feeding envelopes, the combination of a magazine for containing a plurality of superposed envelopes, a feed table having its receiving edge adjacent said magazine, a plurality of rotatable cooperating feed rollers and feed segments between the lower end of 10 15 said magazine and the receiving edge of said table, means for engaging the flap of an envelope to unfold and move said flap into a position between said rollers and segments to be engaged and fed thereby from said magazine 20 onto said table, and means engageable with the outer end portions of said flap and relatively movable with respect thereto for removing any curl therefrom and for lifting the outer end portions of the flap onto said feed table.

25 8. In a device for feeding envelopes, the combination of a frame, a magazine for containing a plurality of superposed envelopes, a feed table having a receiving edge adjacent said magazine, a pair of shafts rotatably mounted in said 30 35 frame, a plurality of rotatable cooperating feed rollers and feed segments mounted respectively on said shafts between the lower end of said magazine and the receiving edge of said table, means for engaging the flap of an envelope to unfold and move said flap into a position between said rollers and segments to be engaged and fed thereby from said magazine onto said table, a pair of laterally spaced members engageable with the outer end portions of said 40 45 flap and relatively movable with respect thereto, and means operatively related to one of said shafts for actuating said pair of members.

9. In a device for feeding envelopes, the combination of a frame, a magazine for containing a plurality of superposed envelopes, a pair of shafts rotatably mounted in said frame, a plurality of rotatable cooperating feed rollers and feed segments mounted respectively on said shafts adjacent the lower end portion of said 50 magazine, means for engaging the flap of the lowermost envelope in said magazine to unfold and move the flap into a position between said

rollers and segments to be engaged thereby for moving the envelope from said magazine, a pair of slide members engageable respectively with the outer end portions of said flap and relatively movable with respect thereto, a rock-shaft rotatably mounted in said frame, actuating means connected to said rock-shaft and slide members, and means operatively related to said rock-shaft and segment shaft for oscillating the rock-shaft. 5 10

10. In a device for feeding envelopes, the combination of a frame, a magazine for containing a plurality of superposed envelopes, upper and lower feed shafts rotatably mounted in said frame, a plurality of feed rollers and feed segments mounted on said upper and lower feed shafts, respectively, adjacent the lower end portion of said magazines, means beneath said magazine for engaging the flap of an envelope to unfold and move said flap into a position 20 25 between said rollers and segments to be engaged thereby for moving the envelope from said magazine, a pair of curl removing members engageable respectively with the outer end portions of said flap and relatively movable with respect thereto for removing the curl therefrom, a rock-shaft mounted in said frame, actuating means operatively related to said rock-shaft and curl removing members, an arm secured to said rock-shaft, a radially spaced roller carried by said lower shaft and engageable with said arm for rotating said rock-shaft in one direction, and resilient means for rotating the rock-shaft in the opposite direction. 30 35

11. In a device for feeding envelopes, the combination of a plurality of cooperating feeding means engageable with the flap of an envelope, and a pair of laterally spaced members engageable with said flap adjacent the end portions thereof and bodily movable transversely with respect thereto for removing any curl therefrom. 40

12. In a device for feeding envelopes, the combination of a plurality of cooperating feeding means engageable with the flap of an envelope, and a pair of laterally spaced members engageable with the flap adjacent the end portions thereof and slidably movable transversely with respect thereto for removing any curl therefrom and maintaining the flap and end portions thereof in operative position to be engaged by 50 said feeding means. 45
